UNITED STATES PATENT OFFICE.

EPHRIAM A. FOSTER, OF SANDUSKY, OHIO.

SPIKE.

1,248,301.

Specification of Letters Patent.

Patented Nov. 27, 1917.

Application filed February 19, 1916, Serial No. 79,354. Renewed August 18, 1917. Serial No. 186,931.

To all whom it may concern:

Be it known that I, EPHRIAM A. FOSTER, a citizen of the United States, residing at Sandusky, in county of Erie and State of Ohio, have invented certain new and useful Improvements in Spikes, of which the following is a specification.

My invention relates to an improvement in spikes and relates more particularly to railroad spikes which are intended to fasten down the rails to the ties, although, of course, they may be used in any other field where applicable, such as in ship building and construction work.

The object of my invention is to produce a spike so constructed as to prevent its working up after once being driven in. This will obviate many of the dangers which are present in railway travel, where there is a possibility of a loose spike permitting the rails to spread so that a wreck is the result. This is accomplished by the provision of a slot in the side of the spike in combination with a curved point, so that upon its being driven in, the curved point will tend to bend the spike, thus preventing its working out.

In the accompanying drawings:

Figure 1 is a perspective view of my spike;

Fig. 2 is a vertical cross section with the effects of driving it in shown in full lines; and

Fig. 3 is a transverse section of the point section of the spike on line 3—3 of Fig. 1.

The spike A is provided with a shank 1 and a head 2, as is customary, and about two-thirds the way down the shank 1, is placed the slot 3, which marks the dividing line between the shank and the point section 4.

The slot 3 is preferably placed on the same side of the shank as the head 2, and extends sufficiently into the shank as to form a substantial yet bendable connection 5, between the shank and the point section 4. As will be noted that portion of the point section 4, on the inner-side of the shank directly below the slot 3 projects out a little farther than the width of the upper portion of the spike.

The point section 4 is provided with a convex surface 6 at the point and the other surface of the point may be either a continuation of the surface of the shank 1, or a cutting away to a point as at 7.

In the utilization of my spike the rail is placed in position and the spike is started downwardly in its desired location. The action of the wood against the curved surface 6 owing to the fact that the point is tapered directly back of this surface will force the pointed section at an angle to the line of driving, causing the bending to take place at the connection 5, as illustrated in Fig. 2. The result of this bending action will be to have the shoulder 9 of the pointed section 4 engage the material of the tie and prevent its working out.

Should there be some reason why the curved surface 6 will not suffice to bend the pointed section, as for instance where there is a knot in the way, the spike will assume the position indicated in dotted lines in Fig. 2 and will still be incapable of working out because of the fact that the spike 1 is thinner than the pointed section 4, and after the fibers of the wood have yielded to the thick section 4, they will immediately contract around the shank 1, and the shoulder 9 will, as before, engage the tie for preventing the removal of the spike.

I claim:

1. A spike having a beveled point, and provided with a comparatively deep kerf adjacent to the point, and which extends in the same general direction as the bevel of the point, thereby forming a sharp upturned barb substantially flush with the side of the spike, said kerf extending into the spike a sufficient distance to weaken it and admit of its bending, and thereby outwardly deflecting the upturned barb when the spike is driven.

2. A spike, the shank of which has a transverse slot, and a point curved on the slotted side and tapering at the rear thereof, whereby upon driving the spike the curved portion of the end will cause it to bend open at the slot whereby to prevent the removal of the spike.

3. A spike the shank of which has a trans-

verse inclined slot, and a point curved on the slotted side and narrowed at the rear thereof, the thickness of the point directly below the slot being greater than the upper portion of the spike, thereby forming a protruding shoulder on the slotted side whereby upon driving the spike the curved

portion of the end will cause the slot to open and cause the shoulder to protrude farther beyond the face of the spike, thereby preventing the removal of the spike. 10

In testimony whereof I affix my signature.

EPHRIAM A. FOSTER.
